MASON'S ALIGNING FIXTURE

Adrian W. Craig and Robert L. Sears, Des Moines, Iowa, and S. Eugene Hubbard, Chicago, Ill.; said Hubbard assignor to said Craig and said Sears, jointly

Application September 30, 1950, Serial No. 187,742

9 Claims. (Cl. 33—85)

1

This invention relates to aligning fixtures suitable for use by a mason in connection with accurately leveling a first course of bricks or other building units, and aligning the subsequent courses of the wall made from such units, which fixtures assure that all courses will be parallel to the first course. The use of such fixtures simplifies the construction of the wall by eliminating the use of level and plumb line during such construction and makes possible the laying of the walls in less time than heretofore.

One object of the invention is to provide an aligning fixture which is an improvement with respect to construction and operation compared with the fixture disclosed in the co-pending application of Craig and Sears, Serial No. 114,976, filed September 10, 1949.

More specifically an object of the present invention is to provide a carriage for a line carrier and an elevating mechanism for the carriage which can be operated from any point along the vertical height of an upright which supports the carriage, thus permitting operation from a convenient point when standing on the ground, or when standing on a scaffold or the like after the first story of a building has been laid.

Another object is to provide an indexing mechanism in the carriage cooperable with spaced holes or the like of the upright for predetermining each course of bricks without the necessity of having to align a pointer with indicating marks on the upright or use some similar arrangement.

Still another object is to provide the indexing mechanism in the carriage also readily operable from any vertical point on the upright and which accurately positions the carriage with respect to the openings provided in the upright, thus permitting equal advance of the line carriers on the various uprights at all the corners of the building.

A further object is to provide an improved line carrier mounted on the upright and provided with a scuff plate arrangement to protect the line from being frayed and broken, the line carrier being also provided with a retracting arrangement which may be operated from a point adjacent the lower end of the upright to permit return of the line carrier to the bottom of the upright with the line clear of the wall so that it does not rub therealong.

2

A further object is to provide other minor improvements in the design of a mason's aligning fixture including an arrangement to tie two adjacent uprights together, a dual line carrier for building double walls, an indexing adjustment to correct for the uprights when mounted at different elevations, a scale shift arrangement on the carriage for shifting the indexing mechanism thereof from one scale of building units to another, and an upright support having means to engage the corner of a wall footing and take up any play in the support.

With these and other objects in view, our invention consists in the construction, arrangement and combination of the various parts of our mason's aligning fixture, whereby the objects contemplated are attained, as hereinafter more fully set forth, pointed out in our claims and illustrated in the accompanying drawings, wherein:

Figure 1 is a perspective view of a mason's aligning fixture embodying our present invention, the fixture being shown mounted on the footing of a wall and stakes for plumbing the fixture being illustrated which may be driven into the ground.

Figure 2 is a sectional view on the line 2—2 of Figure 1 to show the support for the upright of the fixture and one method of mounting it on the footing of a wall.

Figure 3 is a vertical sectional view through the upright of our fixture as taken on the line 3—3 of Figure 2.

Figure 4 is a perspective view of the upper end of the fixture.

Figure 5 is a plan view of two fixtures tied together with a tie rod.

Figure 6 is a perspective view of a carriage and line carrier of our fixture.

Figure 7 is a vertical sectional view through the carriage and indexing mechanism therefor.

Figure 8 is a sectional view on the line 8—8 of Figure 7.

Figure 9 is a sectional view on the line 9—9 of Figure 8.

Figure 10 is a sectional view on the line 10—10 of Figure 8 showing an indexing pawl engaged with the upright.

Figure 11 is a similar sectional view showing the carriage being elevated.

Figure 12 is a similar sectional view showing the indexing pawl released.

Figure 13 is a sectional view on the line 13—13 of Figure 10.

Figure 14 is a perspective view of a line carrier and an auxiliary line carrier for double walled buildings.

Figure 15 is an enlarged plan view of the left-hand line carrier element in Figure 14; and

Figure 16 is a plan view of the right-hand line 10 carrier element of Figure 14.

On the accompanying drawings we have used the reference numeral 20 to indicate a support. The support 20 may be strap-like in character with a vertical part to be bolted as at 21 to a footing 22 of a wall or secured thereto in any desired manner. The support 20 is twisted adjacent its outer end so as to have a horizontal part above which we mount an angle-shaped base 23. Below the base 23 and the support 20 we provide a section of channel 107 having a clamp screw 108 threaded through its flanges and a U-shaped clip 109 swivel-mounted on its inner end to engage the corner of the footing 22. The outer end of the clamp screw has an eye 110 in which a rod or spike may be inserted for tightening the screw to take up any play in the support 20 with respect to the wall footing before our aligning fixture is mounted on the support 22.

Our fixture includes an upright 24 which is 30 preferably a square tube. In its lower end a stub shaft 25 is welded and this is adapted to be clamped against a bead 26 of the base 23 by a U-bolt 27 and a wing nut 28. Referring to Figure 3, it is obvious that the bead 26 permits slight 35 adjustment of the angle of the upright 24 toward the right or left. The upright can also be adjusted in the U-bolt 27 in a vertical plane at right angles to the plane just mentioned. These 40 adjustments are for plumbing purposes.

To aid in plumbing the upright we provide guy tubes 29 in which guy rods 30 are telescopically mounted. The upper ends of the tubes are pivoted at 31 in forked swivel heads 32 which are rotatable about a shouldered stud 33 threaded into a plug 34 welded in the upper end of the upright 24.

Guy stakes 43 are provided at the lower ends of the guy rods 30 for driving into the ground, or the lower ends of the guy rods may be attached in any suitable manner as by nailing to any stationary object that is suitably located.

The guy tubes 29 have caps 35 threaded on their lower ends. Threaded through the sides of the caps are set screws 36 as shown in Figure 3. Additionally the guy rods 30 may be provided with turnbuckles 37 for fine adjustment so that the uprights 24 may be accurately plumbed at the various corners of the building, before construction of the wall is started.

Also when there are two adjacent uprights as for instance at the corner 41 of the building and at a jog 42 in the wall (see Figure 5), a tie rod 38 as shown in Figures 4 and 5, may be provided. In that event the shouldered studs 33 are replaced by somewhat longer ones 33a to accommodate a clamp bracket 39 provided with a set screw 40 for the tie rod 38. This eliminates the necessity of providing two guy arrangements for the upright at the jog 42.

Vertically slideable on the upright 24 is a carriage indicated generally at C and which is best shown in Figures 6, 7, 8 and 9. The carriage C is provided with a plurality of rollers 44, 45, 46, 47, 48, 49 and 49a at various points around the 75

upright so that the carriage may be raised and lowered with respect to the upright with a minimum of friction and effort.

The carriage C may be conveniently raised and lowered by a raising and lowering rope 50 having one end connected to an opening 51 of the carriage (see Figure 7) and its other end connected to an opening 52 thereof. The rope extends upwardly from the opening 51 over a pulley 53 mounted adjacent the top of the upright 24 as shown in Figure 3, then downwardly inside the upright and under a second pulley 54 before returning upwardly to the opening 52. Obviously the rope may be grasped anywhere between the pulleys 53 and 54 and the carriage raised or lowered thereby.

The carriage C supports a line carrier 55 which we have disclosed as being a channel shaped bar provided on one end with a line carrier bracket 56 adapted to carry a mason's line 57. The bracket 56 has a pair of scuff plates 58 which are notched as at 59 so that as shown in Figures 15 and 16, the line approximately contacts the wall surface when the scuff plates are in contact therewith. This affords some protection to the line to prevent it from being frayed and broken at the places where it bends to enter the line carrier brackets 56. The mason's line 57, after passing through the notches 59 of the scuff plates, may be secured to the line carrier 55 by wrapping them around the line holding cleats 60 secured to the line carriers 55.

The line carriers are adjustable toward and away from the wall by having slots 61 therein to slide on sleeves 62 and 63 as shown in Figure 8. The sleeve 62 is merely a spacer between a washer 64, a bolt 65 and the carriage C, the bolt being secured to the carriage by a nut 66. The sleeve 63 is mounted on a clamp bolt 67 on which a clamp handle 68 is screw-threadedly mounted. The clamp handle 68 clamps the web of the line carrier 55 between a washer 69 and a sleeve 70 so that the adjustment can be retained.

The sleeve 63 and the bolt 67 are carried by a cam 71 having a handle 72. The cam is mounted between the flanges 73 and the web 74 of an insert of the cross section shown in Figure 8 which is secured in the front of the carriage C as by rivets or the like 75. The clamp bolt 67 has a square portion 76 slidable in a slot 77 of the carriage C and a slot 78 of the insert 73—74 as shown in Figure 8. The sleeve 63 adjacent its other end is slidable in a slot 79 of the carriage C and a slot 80 of the insert 73—74.

Due to the arrangement just described, when the cam 71 is reversed to the dotted position shown in Figure 7 by swinging the handle 72 from its upward position counterclockwise to its lowered position, the clamp screw 67 and the sleeve 63 are slid rearwardly (to the right) in the slots 77, 78, 79 and 80 to the dotted position and carry with them the line carrier 55, the bracket 56 and the mason's line 57 for a purpose which will hereinafter appear. For swinging the cam handle 72 in this manner, we provide a hooked rod 81 which may be of sufficient length to reach to any convenient position of operation along the upright 44.

Within the carriage C we provide an indexing mechanism including a channel-shaped pawl box 82 secured to the carriage by a clamp screw 83 and a wing nut 84. The screw extends through a lateral slot 85 of the carriage C so that the pawl box can be shifted laterally and then locked either at the lower end of the slot illustrated in

Figure 8 by a channel-shaped clamp plate 88 or adjacent the upper end of the slot when the clamp plate is reversed for changing scales as will hereinafter appear.

The pawl box is also vertically adjustable relative to the carriage C and this is accomplished by providing a vertical slot 111 for the clamp screw 83. A cover plate 112 is provided for the pawl box to prevent mortar and other foreign material from dropping into it.

Within the pawl box a pawl 87 is pivoted on a pivot bolt 88 and is constrained to swing clockwise in Figure 10 by a spring 89. The pawl is thus constrained to enter any one of a series of spaced openings 90 in the upright 24 and due to the angle of shoulders 91 and 92 of the pawl the carriage may be freely raised relative to the upright as shown in Figure 11 but will be locked against downward movement as shown in Figure 10 whenever the pawl enters one of the openings 90. The pawl, however, may be released against the bias of the spring 89 as in Figure 12 and this is accomplished by the following described mechanism.

A pawl release crank 93 is provided, the crank pin 94 of which is located in an opening 95 of the pawl. As long as the crank pin 94 is in the position shown in Figures 10 and 11, the spring 89 may rotate the pawl clockwise. When the crank is rotated clockwise to the position shown in Figure 12, it holds the pawl in the released or unlocked position.

The crank 93 is mounted for oscillation in the pawl box 82 and has a pawl release lever 96 mounted thereon and provided with a pair of eyes 97 and 98. The ends of a pawl release rope 99 are connected with the eyes 97 and 98 and intermediate the ends of the rope it extends upwardly over a top pulley 100 then downwardly inside the upright 24 and under a bottom pulley 101. Thus the pawl 87 may be rendered operable as in Figures 10 and 11 or released as in Figure 12 from any convenient position along the upright.

When a double wall is to be laid as in Figure 14, it is desirable to have a second mason's line 57a in a predetermined position with respect to the first line 57. We accomplish this by providing a second line carrier bracket 56a supported by means of a rod 102 and a clamp bracket 103 from the line carrier 55 as shown in Figure 14. The rod may be provided with a set collar 103 to serve a purpose which will hereinafter be described.

Practical operation

In the operation of our mason's aligning fixture, one of the fixtures as shown in Figure 1 is mounted at each corner 41 of the building and additional ones may be located at jogs such as indicated at 42 in Figure 5. The lowermost indexing opening 90 of each upright 24 is located at approximately the same elevation. So that the courses of building units in the wall will be level, the pawl boxes may then be vertically adjusted relative to the carriages C so that all line carrier brackets 56 carry the line 57 in a true level horizontal plane.

The uprights 24 are plumbed after the stakes 43 are located by means of the set screws 36 provided for the guy tubes and rods 29 and 30 (and the turnbuckles 37 if used). This insures that the line carriers 55 will be advanced in a true vertical path for keeping the corners and jogs of the wall vertical.

After the mason's line 57 (and 57a if used) are strung through the line carrier brackets 56 (and 56a) the first course of brick is laid, the carriages C, of course, being at the lower ends of the uprights. After the course on one wall is laid and the mason turns the corner, his helper may index the carriage C on the upright 24 at the starting corner of the wall upwardly one opening 90 on such upright. This is accomplished by grasping the rope 50 and raising it whereupon the carriage will be raised with the pawl 87 being forced out of the lowermost opening 90 due to the incline of its shoulder 92 dragging along the upright 24 as shown in Figure 11. The carriage is advanced upwardly until the pawl "clicks" into the next opening 90 and then the rope 50 is lowered for seating the pawl shoulder 91 against the lower edge of this opening as in Figure 10. The other fixtures are likewise adjusted one wall length behind the mason so that by the time he completes one circuit of the wall, the line is in position for the next course of building units.

After the first story has been completed (and disregarding the auxiliary line carrier 56a which will be described later), it is desirable to move the line 57 back so that it clears the wall and particularly at its corners instead of dragging on the wall as the carriages are returned to the lower ends of the uprights. This is accomplished by swinging the cam handle 72 from the full-line position of Figure 7 to the dotted line position either directly by hand or by using the hook rod 81. The carriages are moved down again to the lower ends of the uprights and this is accomplished by first releasing the pawls 87 by pulling downwardly on the ropes 99 to rotate the pawl release cranks 83 to the position shown in Figure 12. After the carriages are lowered, the rope 99 is raised for returning the pawl release crank to the position shown in Figures 10 and 11 for automatic indexing again as the carriages are raised step by step.

The fixtures are then remounted at the top of the first story and in place of the stakes 43 the lower ends of the guy rods 30 may be nailed or otherwise suitably attached to the second story floor. The cam levers 72 are swung again to the full line position of Figure 7 for moving the line carriers 55 forwardly to hold the lines 57 in the proper vertical planes (the outer surfaces of the first story walls).

The arrangement of indexing mechanism and the ropes for controlling them and the movement of the carriages vertically along the uprights makes for convenience of operation and facilitates operation to such an extent that the indexing can be accomplished in a minimum of time which leaves the mason's helper with time enough to furnish the mason with building units and mortar in the usual manner. A mason and his helper when using our fixtures can accordingly build up a wall in much less time than heretofore possible.

During the construction of a double wall, the auxiliary line carrier 56a illustrated in Figure 14 is used and as the carriages on the various uprights 24 are advanced upwardly, the auxiliary line 57a as well as the line 57 will be elevated step by step as the courses of building units are laid. When the carriages are to be lowered, the set screws 105 may be loosened and the rods 102 removed and then after the uprights are reset for the second story, the rods may be replaced whereupon the set collars 104 will serve to again

accurately space the auxiliary lines 57a with respect to the main lines 57.

With respect to construction and operation of the clamp plate 86 in Figure 8, it will be noted that in addition to the openings 90 there are also openings 90a and the spacing of the openings 90 may be different than the spacing of the openings 90a. For instance 2" and 2 2/3" are standard building unit measurements. These openings can be accurately drilled or punched to these spacings and to change from one to the other it is merely necessary to shift the pawl box 82 to align with the openings 90a instead of the openings 90. This is accomplished by removing the wing nut 84 and the clamp plate 86, sliding the clamp screw 83 from the bottom of the slot 85 in Figure 8 to the top thereof, and reversing and replacing the clamp plate after which the wing nut is screwed on to the screw again.

The rollers 44, 45, 46, 47, 48, 49 and 49a provided for the carriage C make it easy to move it along the upright 24 and the cam 71 provides a ready means for retracting the line from the surface of the wall so that it is not dragged along this surface as the carriage is returned downwardly. The various features of improvement herein disclosed increase the usefulness of the fixture and provide for simpler and more accurate operation thereof.

Some changes may be made in the construction and arrangement of the parts of our mason's aligning fixture without departing from the real spirit and purpose of our invention, and it is our intention to cover by our claims any modified forms of structure or use of mechanical equivalents which may be reasonably included within their scope.

We claim as our invention:

1. A mason's aligning fixture having a plumbed upright with a carriage vertically movable thereon and a line carrier mounted on said carriage, a pair of ropes, one of said ropes being connected with said carriage, pulleys adjacent the top and pulleys adjacent the bottom of said upright, said ropes extending therearound, said one of said ropes being adapted for moving said carriage with respect to said upright by manipulation of said rope, and indexing means carried by said carriage for moving said carriage step-by-step along said upright, said indexing means including a pawl biased to engage said upright and means to manually release said pawl from said upright comprising the other one of said ropes, the ends thereof being connected to said release means.

2. In a mason's aligning fixture having a plumbed upright with a carriage vertically movable thereon and a line carrier mounted on said carriage, said carriage having an indexing mechanism including a pawl normally biased toward said upright, said upright having spaced openings to receive said pawl at predetermined vertical positions corresponding to building units, said carriage being freely movable upwardly and prevented from downward movement by said pawl, flexible means having its ends operatively connected with said pawl for retracting it, and pulleys at the top and bottom of said upright for said flexible means to extend around so that said pawl may be retracted from a position adjacent the bottom of said upright.

3. In a mason's aligning fixture having a plumbed upright with a carriage vertically movable thereon and a line carrier mounted on said carriage, a rope connected with said carriage, pulleys adjacent the top and bottom of said up-

right, said rope extending therearound for moving said carriage with respect to said upright by manipulation of said rope, said carriage having an indexing mechanism including a pawl normally biased toward said upright, said upright having spaced openings to receive said pawl at predetermined vertical positions corresponding to building units, and a second rope with pulleys at the top and bottom of said upright and connected with said pawl for releasing the same.

4. In a mason's aligning fixture having a plumbed upright with a carriage vertically movable thereon, a line carrier mounted on said carriage and a line carried thereby and having vertical building unit joint indicating marks, said upright being provided with spaced openings, indexing mechanism carried by said carriage and including a pawl for step-by-step cooperation with said openings, means on said carriage for rendering said pawl operable or inoperable, a pulley at the bottom and a pulley at the top of said upright, and a flexible element connected with said means and extending upwardly over said first pulley, then downwardly under said second pulley and upwardly again to said means.

5. In a mason's aligning fixture having a plumbed upright with a carriage vertically movable thereon and a line carrier mounted on said carriage, a rope connected with said carriage, pulleys adjacent the top and bottom of said upright, said rope extending therearound for moving said carriage with respect to said upright by manipulation of said rope, said line carrier being retractable relative to said carriage, and a cam for effecting such retraction.

6. In a mason's aligning fixture having a plumbed upright with a carriage vertically movable thereon and a line carrier mounted on said carriage, a rope connected with said carriage, pulleys adjacent the top and bottom of said upright, said rope extending therearound for moving said carriage with respect to said upright by manipulation of said rope, said line carrier being retractable relative to said carriage, a cam for effecting such retraction and an extension for operating said cam from a position vertically remote from said cam.

7. In a mason's aligning fixture having a plumbed upright with a carriage vertically movable thereon, a line carrier mounted on said carriage and a line carried thereby, said line carrier having a pointed end, the sides of the point having flange-like scuff plates thereon arranged at an acute angle to each other and notched to receive said line so that the line clears the corners of the wall, said line having vertical joint indicators thereon.

8. In a mason's aligning fixture having a plumbed upright with a carriage vertically movable thereon and a line carrier mounted on said carriage, said upright being provided with spaced openings, indexing mechanism carried by said carriage for step-by-step cooperation therewith, and an auxiliary line carrier mounted on said first line carrier for carrying an auxiliary line spaced from a line carried by said line carrier for use in the construction of a double wall, said auxiliary line carrier being adjustable toward and away from said first line carrier to vary the total thickness of said double wall.

9. In a mason's aligning fixture having a plumbed upright with a carriage vertically movable thereon and a line carrier mounted on said carriage, a support for said upright including a vertical flange having a bead thereon to be en-

9

gaged by said upright, a U-bolt to secure said upright to said flange and against said bead, an indexing mechanism in said carriage, said upright having spaced openings to coact therewith to index said carriage at predetermined vertical positions corresponding on said upright to building units.
